UNITED STATES PATENT OFFICE.

WILLIAM C. SHARKEY, OF PHILADELPHIA, PENNSYLVANIA, ASSIGNOR TO CLARENCE A. GOSLIN, OF PHILADELPHIA, PENNSYLVANIA.

VENDING-MACHINE.

1,112,333.

Specification of Letters Patent. Patented Sept. 29, 1914.

Application filed December 27, 1913. Serial No. 802,972.

To all whom it may concern:

Be it known that I, WILLIAM C. SHARKEY, a citizen of the United States, residing in Philadelphia, Pennsylvania, have invented 5 certain Improvements in Vending-Machines, of which the following is a specification.

One object of my invention is to provide a relatively simple and substantial mechanism for vending packages of candy, chewing gum and the like, it being especially desired that the mechanism shall be inexpensive to construct, and have its parts so arranged that they shall not easily get out of order or require repair.

15 The invention also contemplates novel means for preventing the introduction of coins after all of the packages or other articles have been discharged and the arrangement and design of the apparatus as a whole 20 is such as to reduce to a minimum the number of moving parts.

It is also desired to provide a device of the above noted type in which means shall be included for preventing the noisy operation of 25 any of its parts and in which the arrangement and construction of parts shall be such that it shall be practically impossible for any one to abstract a piece of candy or gum without placing in the machine a coin of the 30 proper denomination, it being also desired to prevent the securing of more than one piece of the goods in the machine by the insertion of each coin.

These objects and other advantageous 35 ends I secure as hereinafter set forth, reference being had to the accompanying drawings, in which:—

Figure 1 is a perspective view of a vending machine constructed according to my 40 invention; Figs. 2 and 3 are two elevations further illustrating the invention, showing the mechanism in its normal position, and also in the position occupied just before the last package has been removed; 45 Figs. 4, 5 and 6 are perspective views illustrating the detail construction of certain of the parts of the invention; Fig. 7 is an elevation, partly in section, illustrating the relative positions of certain of the parts 50 after a coin has been inserted; Figs. 8 and 9 are inverted plans, partly in section, of the parts shown in Fig. 7, illustrating the operation of the apparatus; Fig. 10 is a frag-

mentary perspective view illustrating the magnet and its associated parts.

55 In the above drawings, 1 represents a metallic or other suitable box constituting an inclosing casing which may be open on its rear face or be provided with any suitable door or cover, as may be desired. As shown in Fig. 1, the front face of this casing is cut away to provide an opening which for the most part is closed by a plate 2 of non-magnetic metal, such as brass, bent to have an angular section and provided with an elongated coin slot 3. The plate 2 not only extends upon the inside surface of the front member of the casing but also projects immediately adjacent the side 1^a thereof, as indicated at 4, and upon it I mount a permanent magnet 5, which extends substantially parallel with and immediately adjacent to the plane of the slot 3. As a result of this construction, an iron washer introduced through said slot would cling to or be deflected by the lower end of the magnet 5 instead of falling into an operative position, as hereafter explained.

70 Pivotedly mounted on a suitable pin or pindle 6 projecting inwardly from the inside surface of the front of the casing is an operating lever 14 of the construction shown in Fig. 4, normally held in the position shown in Fig. 2 by a spring 7 acting on one of its arms 8. Said lever consists of a bar having a projecting lug on one side provided with a bearing for the pivot pin 6. From this pin the lever extends toward the adjacent side of the casing and thereafter extends substantially parallel therewith immediately 75 adjacent the coin slot 3, beyond whose lower edge it is provided with an off-set or recessed portion 10 for the reception of the turned up end 12 of an ejecting lever 13 hereafter referred to in detail. The lower 80 portion of the rearmost edge of this lever 14 is flanged as indicated at 15 so as to normally extend across the plane of the slot 3 and the flange is extended to provide a forwardly projecting abutment 16. As shown in Figs. 8 and 9, this is spaced away from the lower end of the main portion of the lever 14 by a distance somewhat greater than the thickness of a coin x , which the machine 85 is designed to receive.

100 Separably fixed to or formed integral with

the lever is an arm 17 in the form of a hollow angular structure forming an operating member projecting through an opening in the side 1^a of the casing 1, with its top surface preferably horizontal and its outer edge formed on a curve substantially concentric with the pivot pin 6. Under the action of the spring 7, the lever 14 is normally held in such a position that this operating member occupies the position shown in Figs. 1 and 2.

In order to prevent noise when the lever under the action of the spring returns to its normal position, I insert in a suitable dovetailed or undercut recess in the flange 15 a body 15^a of rubber or the like. Just below the lower end of the lever 14, I provide a horizontally elongated abutment 18 for the purpose of temporarily supporting a coin, and in the present instance this abutment consists of an angular rib formed integral with and projecting from the inner surface of the front of the casing, its end most distant from the side 1^a of the casing being notched or provided with a shoulder 18^a so placed as to prevent a backward movement of a coin which has once passed over it.

The ejecting lever, as shown in Fig. 6, consists of a relatively flat bar 13 having a side arm 19 which extends across the operating lever and whose end is provided with the bent up portion 12 above referred to. This lever is pivoted on a pin 20 projecting from the inner face of the casing front adjacent the top, and it is of such length that its lower end swings immediately above the bottom of the casing, being turned up substantially at right angles to its plane as indicated at 21. This lever is so placed and proportioned that when the operating lever 14, under the action of its spring 7, occupies the position shown in Fig. 2, the turned up end 12 lies within the recessed part 10 of said lever with its outer face substantially flush with the adjacent main portion thereof. As a consequence the ejecting end 21 is held to one side of the bottom of the casing, immediately adjacent or in contact with a partition 22 which with the front, side and back of the casing, forms a coin receptacle 23.

All packages or articles to be vended are contained within a vertically placed chute or holder 24, which in the present instance consists of a sheet of tin having a front and two sides 25 and 26 provided with flanges extending toward each other. This package holder is held in place within the casing by a screw 27 which also holds in place one end of the spring 7, and the front of said holder is spaced away from the inside face of the front of the casing by lugs 28 and 29 formed integral with the latter so that the ejecting lever 13 is free to swing between it and said face. The lower end and the sides of the holder are cut away, as indicated at 30, to

permit the arm 21 to freely move into and across the bottom of said holder toward the package outlet opening 31 formed in the lower end of the second side 1^b of the casing.

The packages *g* which the machine is designed to vend, are placed in a column within the holder 24 whose width between its sides 25 and 26 is therefore substantially equal to the length of each of said packages, and whose depth between the flanges of said sides and its front face is equal to the width of the packages. This column of packages is pressed downwardly by any suitable actuating member such as a weight 32, preferably consisting of a mass of metal substantially of the same width and breadth as the packages and having heads or ends 33 which project on opposite sides of the plane of its flat central portion.

The outlet opening 31 has a valve or automatic stop which in this case has the form of a lever 34 pivoted to the casing body by a pin 35 in such a manner that one of its arms extends downwardly within the casing, immediately adjacent the opening 31, while its other arm extends in the opposite direction and normally rests against the side 1^b so as to prevent said first arm from being pushed inwardly, it being noted that an integral rib or inwardly projecting lug 34^a extends immediately above the opening 31 so as to effectively prevent the malicious introduction of a knife blade, pin, or the like, for the purpose of opening the valve 34. The width of said lever or valve is substantially equal to the length of the outlet opening 31 and it is normally held in the position shown in Fig. 2 by a flat spring 36 acting on its upwardly extending arm, the spring in the present instance being retained in place by one of the screws 37 employed to hold a lock 38 in place on the inside surface of the side 1^b. In the present instance this lock is designed for use in retaining in place a cover plate (not shown), which is of such dimensions as to fit within the rear face of the casing. Said plate adjacent one end has a pair of projecting pins designed to enter holes 39 in the top end of the casing and at the opposite end has a second pin designed to enter a hole 40 in the bottom end of said casing. By means of a suitable key, the mechanism of the lock 38 may be operated to project a bolt whereby said cover plate may be prevented from removal.

Under conditions of use, the holder 24 is filled to the level of the upper ends of its side flanges by a column of packages or other articles to be vended, and the weight 32 is placed on the top of said column as shown in Fig. 2. Thereafter when a coin of suitable denomination is delivered through the slot 3 to the mechanism within the casing, it falls downwardly between the inner edge of the structure 17 and the adjacent

face of the lever 14, and is finally stopped by the rib 18 and the inner face of the lower portion of the flange 15. Obviously, if the coin is of less than the predetermined diameter, it will not be supported upon these members but will immediately drop into the coin receiving space 23 so that the revolution of the lever 14 on its pivot has no effect upon the ejecting member 13.

If the object introduced through the coin slot should be an iron disk or washer, it would be held by the attraction of the magnet 5 from falling into the position noted, so that as the lever 14 was turned on its pivot, it would be merely pushed out of engagement with said magnet by the inner edge of the operating member 17 and as before noted, would fall into the coin receiving space without affecting the ejecting member. If, however, the coin lodges as noted upon the rib 18 and the inner lower portion of the flange 15, as shown in Fig. 7, the turning of the lever 14 on its pivot causes the lip or abutment 16 to engage said coin (Fig. 8), and to move it laterally along the rib 18. As said coin is moved, however, it engages and carries with it the up-turned end of the arm 19, thus swinging the ejecting lever 13 on its pivot from the position shown in Fig. 2 into the position shown in Fig. 3. Such movement of this ejecting lever causes the lower end 21 thereof to be moved under the bottom of the package holder 24, thus bringing it into engagement with the lowermost package γ and causing this to be pushed out from under the column of packages. It is noted, however, that before the lever 13 has been moved sufficiently to cause its end 21 to move a package far enough to open the valve 34, the coin passes the shoulder 18^a, and falls behind it without dropping off the rib 18. Since it is now not possible for the coin to move back on the rib 18, it is obviously impossible to secure a package γ and thereafter allow the parts to return to their normal positions with the coin still resting on said rib, and consequently the continued use of a single coin to obtain an indefinite number of packages is effectually prevented. The continued forward movement of the end 21 of the lever 13 causes one of the packages to be brought into engagement with the lever valve 34 which is thereby moved into the position shown in Fig. 8, while the package projects through the opening 31 in the side of the casing.

The continued movement of the lever 14 on its pivot causes the coin α to be moved off of the rib 18 although it is still confined between the abutment 16 and the up-turned end 12, until the pressure on the operating member 17 is relaxed. Immediately thereafter, under the action of gravity, the coin drops into the receptacle 28, and the spring

7 causes the lever 14 to be turned on its pivot from the position shown in Fig. 3 into that shown in Fig. 2.

Owing to the engagement of the up-turned end 12 of the arm 19 with the side of the recess 10 in the lower end of the lever 14, the ejecting lever 13 is likewise drawn back into and held in its normal position. The weight 32 with the column of packages γ thereafter moves bodily downward so as to bring another package into position to be engaged by the end 21 of the ejecting lever 13. The end of the package which has been forced through the outlet opening 31, may now be grasped and withdrawn from the casing, after which the spring 36, acting on the upper arm of the lever valve 34, returns this to its normal closed position.

After the last package of the column has been discharged as shown in Fig. 3, the weight 32 rests upon the bottom of the casing, so that one of its heads 33 is engaged by the arm 21 of the ejecting lever 13 as this is drawn back toward its normal position by the spring actuated lever 14. Said head thereafter prevents the further return movement of said two levers and holds the lever 14 in such a position that the flat side of the operating member 17 lies immediately adjacent the inside face of the brass plate 2, thus effectually preventing the introduction of any more coins through the slot 3 until such time as the weight 32 is removed, as when the holder 24 is again filled, after which the ejecting lever 13 and the operating lever 14 are free to return to their off positions.

By reason of the peculiar shape and mounting of the lever valve 34, it is practically impossible to open this from the outside, while, as above noted, the operation of the machine whereby it might be caused to deliver a number of packages for a single coin, is also prevented.

The buffer 15^a effectually prevents objectionable noise as the lever strikes the side of the casing when returning to its normal position after operation, and the construction as a whole is simple and compact.

I claim:

1. The combination in a vending machine, of a casing having a coin slot; an operating lever, extending edgewise substantially parallel with the wall of said casing adjacent the slot and having its edge portion below the slot recessed to form an abutment shaped to engage the edge and one face of a coin and coöperate with a part of the casing to temporarily support said coin; with an ejecting lever pivoted adjacent the first lever and having a portion intermediate its ends extended across the operating lever, said portion including a projecting part formed to be engaged and moved by

the latter lever when it moves in one direction and operatively connected to the operating lever by the coin when said lever moves in the opposite direction.

5. The combination in a vending machine, of a casing having a coin slot; with a pair of pivoted levers within the casing, one of which extends edgewise substantially parallel with and is spaced from an adjacent wall of the casing with a portion of its edge below said slot provided with a recess, the other lever having an arm extending from an intermediate portion across the first lever and projecting into the recess thereof so as to be moved thereby under predetermined conditions, a portion of said casing and the adjacent portion of the first lever being formed to support a coin between them in position to operatively connect said levers.

20. 3. The combination in a vending machine of a casing having a coin slot; an operating lever extending edgewise substantially parallel with and supported adjacent one wall of the casing, said lever having a portion of its edge below said slot provided with a recess and having a slotted portion formed to cooperate with a part of the casing to support a coin in a position adjacent said recess; with an ejecting lever pivotally mounted at its upper end and having its lower end formed to eject an article, said ejecting lever having a right angled extension intermediate its ends projecting across the operating lever and turned into the recess thereof in position to be moved directly by said lever under certain conditions, and through the medium of the coin under other conditions.

40. 4. The combination in a vending machine of a casing having a coin slot; an operating lever extending edgewise substantially parallel with and supported adjacent one wall of the casing, said lever having a portion of its edge below said slot provided with a recess and including a slotted portion cooperating with a portion of the casing to support a coin adjacent said recess; an ejecting lever pivotally mounted at its upper end and having its lower end formed to eject an article, said ejecting lever having a right angled extension intermediate its ends projecting across the operating lever and turned into the recess thereof in position to be operatively connected to said lever through the coin, said operating lever being pivotally mounted between its ends; and a spring connected to the upper end of the operating lever and to the casing.

60. 5. The combination in a vending machine of a casing having a coin-supporting abutment; a lever mounted in the casing having a lower portion extending substantially parallel with a wall of the casing and recessed on a side presented toward said abutment,

said recessed portion adapted to cooperate with said abutment to temporarily support a coin by its edges, a wall of the recess being in position to engage the face of the coin; and an ejecting lever pivotally mounted at its upper end back of the first-named lever and having an arm normally extending between a portion of the operating lever and one face of the coin delivered thereto.

6. The combination in a vending machine of a casing having a coin supporting abutment; a lever mounted in the casing having a lower portion extending substantially parallel with a wall of the casing and recessed on a side presented toward said abutment, said recessed portion adapted to cooperate with said abutment to temporarily support a coin by its edges, a wall of the recess being in position to engage the face of the coin; and an ejecting lever pivotally mounted at its upper end back of the first-named lever and having an arm normally extending between a portion of the operating lever and one face of the coin delivered thereto; said abutment being shorter in length than the path of movement of the cooperating end of the operating lever.

7. The combination in a vending machine of a casing; an operating lever mounted therein having a lower portion presented edgewise toward an opposing wall of the casing and provided with a recess, said lever having a slotted part cooperating with a part of the casing to support a coin adjacent said recess; an ejecting lever having an arm extending across the operating lever and turned into said recess in position to be operatively connected to said lever by the coin, and a spring holding the operating lever in normal position.

8. In a vending machine, the combination of a casing having a coin slot; an operating lever adjacent said slot having an edge portion below the slot recessed to form an abutment opposing the wall of the casing and cooperating with an abutment of said casing to support a coin; an ejecting lever pivoted adjacent the operating lever and having a projecting arm extending across the operating lever in position to be operatively connected thereto by the coin when the latter lever moves in one direction; a package actuating member in the form of a weight having a head; and means for guiding the head of said member into holding engagement with the ejecting lever when the last package has been discharged, to cause it to retain the operating lever in a position to close the coin slot.

9. The combination in a vending machine of a casing; an operating lever, an ejecting lever in the casing back of the operating lever, said ejecting lever being pivotally mounted at its upper end and having an arm extend-

ing from an intermediate portion toward and across the operating lever and having a right angled portion to be engaged thereby when said operating lever is moved in 5 one direction; an abutment on the operating lever; means for guiding a coin into a position between said abutment and the end of the ejecting lever arm; means for temporarily supporting a coin in such position; 10 and means for actuating the operating lever to cause movement to be transmitted therefrom through a coin to the ejecting lever.

10. The combination of a casing having a substantially horizontal abutment and a coin 15 slot; a flanged operating lever pivoted within the casing having a coöperating abutment in position to temporarily support a coin between the body of the lever and said first-named abutment with its edges engaged by 20 the flange of the lever and the abutment on the casing; and an ejecting lever pivotally mounted in the casing having an intermediate portion provided with an arm which projects toward the operating lever, said 25 arm having an extremity bent and extending across the operating lever and projecting

between the body of the operating lever and the coin, said ejecting lever also having an ejecting arm.

11. The combination in a vending machine 30 of a casing having a coin slot and provided with a substantially horizontal supporting abutment; an operating lever pivoted to the casing having a slotted portion place to co-operate with said abutment to support a 35 coin and formed to cause lateral movement of the coin off of the abutment when said lever is operated; with an ejecting lever mounted to move in a plane parallel to the plane of movement of said operating lever 40 and having a portion extending between one side of the operating lever and a coin when the latter is resting on the abutment, so as to be moved by said coin.

In testimony whereof, I have signed my 45 name to this specification, in the presence of two subscribing witnesses.

WILLIAM C. SHARKEY.
